US00D776653S

(12) **United States Design Patent** (10) **Patent No.:** **US D776,653 S**
(45) **Date of Patent:** ** *Jan. 17, 2017

(54) **ELECTRONIC DEVICE**

(71) Applicant: **Apple Inc.**, Cupertino, CA (US)

(72) Inventors: **Jody Akana**, San Francisco, CA (US); **Bartley K. Andre**, Palo Alto, CA (US); **Shota Aoyagi**, San Francisco, CA (US); **Anthony Michael Ashcroft**, San Francisco, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Matthew Dean Rohrbach**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Eugene Antony Whang**, San Francisco, CA (US); **Rico Zörkendörfer**, San Francisco, CA (US)

(73) Assignee: **Apple Inc.**, Cupertino, CA (US)

(*) Notice: This patent is subject to a terminal disclaimer.

(**) Term: **14 Years**

(21) Appl. No.: **29/514,931**

(22) Filed: **Jan. 18, 2015**

Related U.S. Application Data

(63) Continuation of application No. 29/513,920, filed on Jan. 6, 2015, now Pat. No. Des. 774,505, which is a continuation of application No. 29/513,921, filed on Jan. 6, 2015.

CLAIM

The ornamental design for an electronic device, as shown and described.

DESCRIPTION

FIG. 1 is a closed top front perspective view of an electronic device showing our new design;

FIG. 2 is a closed bottom front perspective view thereof;

FIG. 3 is a closed top rear perspective view thereof;

FIG. 4 is a closed bottom rear perspective view thereof;

FIG. 5 is a closed front view thereof;

FIG. 6 is a closed rear view thereof;

FIG. 7 is a closed left side view thereof;

FIG. 8 is a closed right side view thereof;

FIG. 9 is a closed top view thereof;

FIG. 10 is a closed bottom view thereof;

FIG. 11 is an open top front perspective view thereof;

FIG. 12 is an open top rear perspective view thereof;

FIG. 13 is an open bottom front perspective view thereof;

FIG. 14 is an open bottom rear perspective view thereof;

FIG. 15 is an open front view thereof;

FIG. 16 is an open rear view thereof;

FIG. 17 is an open left side view thereof;

FIG. 18 is an open right side view thereof;

FIG. 19 is an open top view thereof; and,

FIG. 20 is an open bottom view thereof.

The dashed broken lines represent structure or features that form no part of the claimed design.

The oblique shade lines represent a transparent surface.
